UNITED STATES PATENT OFFICE.

WILLIAM S. LEE, OF CHARLOTTE, NORTH CAROLINA.

INSULATOR-CLAMP.

1,140,603.

Specification of Letters Patent. Patented May 25, 1915.

Application filed July 8, 1913. Serial No. 777,867.

To all whom it may concern:

Be it known that I, WILLIAM S. LEE, a citizen of the United States, residing at Charlotte, in the county of Mecklenburg and State of North Carolina, have invented new and useful Improvements in Insulator-Clamps, of which the following is a specification.

This invention relates to improvements in a device for clamping electric conducting wires to insulators, and has for its object to provide a strong simple device for the purpose, which may be easily secured in place under adverse conditions, said device being made of as few different parts as possible consistent with the requirements, and with the least number of separate fastening members.

The invention further consists in forming the clamp of a plurality of sections each section being substantially a duplicate of the other section or sections, and each provided with an integral member adapted to engage an integral complementary member on the adjoining section when said like sections are brought together to engage between them the conducting wire, said members forming a fastening means for the clamp sections above said wire. Removable fastening means below the conductor serve the double purpose of securing said conductor to the clamp and the clamp to the insulator. Furthermore, the connected members above the conductor prevent the latter being lifted or removed in any manner from the clamp, and also prevent lateral strain on the conductor bending or breaking the parts of the clamp that grip the wire.

Another object of the invention is directed to a shield for the conductor that surrounds or partly surrounds the same, and is retained in position thereon by the clamp, said shield extending a suitable distance along the conducting wire on each side of the clamp to prevent destructive arcing between the conductor and the insulator support or other adjacent part.

With these and other objects in view, the invention consists of the combination and arrangement of parts hereinafter described and pointed out in the appended claims, reference being had to the accompanying drawings, in which—

Figure 1 is a side elevation of the improved clamp applied to an insulator and supporting an electric conductor and shield therefor. Fig. 2 is a plan view of a portion

of the same. Fig. 3 is an elevation of the clamp viewed at a right angle to Fig. 1. Fig. 4 is a perspective view of the invention. Fig. 5 is an elevation of a modified form of the clamp.

In the drawings 10 indicates an insulator of any approved type, to the top of which is secured a clamp 11 for holding an electric conductor or transmission wire 12. In the present instance the clamp 11 is formed of two like sections 13 of semi-circular form and which may have a semi-circular cross section, as shown. Projecting laterally and vertically from the corresponding end of each section is an extension preferably in the form of a lug or gripping member 14. A gripping or extension 15 projects from the other end of each section in a manner similar to the lugs 14. The lugs or members 14, 15 of each section lie in a plane and at their lower ends lie close to the adjacent complementary members 15, 14 of the other clamp when said clamp is in position on the insulator. The upper ends of the members 14, 15 are separated from each other sufficiently far to form a socket or yoke 16 in which the conductor 12 is supported and clamped. In the upper end of each lug or member 14 is a slot 17 with which removably engages a hook-shaped end 18 formed on the end of a transverse or horizontally extending plate 19 projecting from the upper end of the lug or member 15. Holes are bored through the members 14, 15, to receive a bolt 20, by means of which the clamp sections are firmly secured together and the conductor gripped between the spaced upper ends of said members. From the above description it will be evident that each clamp section when constructed as described presents dissimilar ends.

The sections 13 of the clamp are as previously stated, substantially alike, and any two may be connected together to form a complete clamp. By this means no trouble is experienced when assembling the clamp by unintentionally having two members which do not fit together as would be the case were the sections dissimilar.

To assemble the clamp the hook-shaped ends 18 are passed through the slots 17 and the clamp folded down over the conductor 12. This interlocks the clamp sections and prevents their disconnection by a lateral movement from each other at the interlocked point. It is to be noted that the

upper ends 21, 22, of the lug or members 14, 15, incline slightly toward each other, and are held at the proper distance apart by the hooks 18. When therefore, after connecting 5 the clamp sections, the same is to be attached to an insulator, the two sections 13 are drawn together until the upper ends 21, 22, of the lugs or members grip the conductor, the semi-circular portions of the clamp having in the meantime been placed 10 around the top of the insulator. The bolts 20 are now inserted in the openings in the lugs 14, 15, and the nuts 23 screwed tight. The tightening of these nuts presses the 15 clamp sections about the top of the insulator 10 and the members 14, 15 against the conductor, the connection at the upper ends of these members prevents them spreading, and at the same time tends to increase 20 the clamping action of the members on the conductor so that the latter is held tightly in the clamp. The plates 19 which extend between the members 14, 15 besides securing the upper ends of said members 25 together also prevent the conductor being lifted or removed from the clamp.

Much trouble has been experienced by the formation of arcs between the conducting wire and the insulator support or other 30 object in the neighborhood thereof, particularly when the conductors are carrying currents of high tension. These arcs tend to destroy the conductor by forming holes or pits therein, honeycombing the same and 35 weakening the tension thereof, thus causing it to break, and causing the loss at times of a long stretch of expensive wire. To overcome this fault a shield is provided which protects the conductor from any arc 40 that may be formed. This shield comprises a strip of suitable material arranged so that any arc formed near the insulator will pass from the shield and not directly from the conductor; the shield is preferably arranged 45 surrounding or partly surrounding the conductor and extending along the same on each side of the insulator a suitable distance. In the present instance the shield 24 is made of a strip of metal different from 50 the conductor bent into U-form, open at the top and extending wholly around the under side of the conductor as clearly shown in Fig. 3, and up above the conductor for a short distance, the upper extending portions 55 lying in parallel planes. The shield lies between the conductor and the lugs or members 14, 15, and is secured to the conductor by said members at the same time the clamp 11 is fixed to the insulator. The length of 60 the shield 24 or the distance it extends along the wire from the insulator on each side is governed by the size of the insulator and the voltage of the current carried by the conductor. Any arcing that may occur will 65 extend from the shield and the latter be

burned by the current instead of the conductor. There being no strain or tension on the shield the latter will last much longer under the destructive influences of the arcs formed than would the conductor, and furthermore, they may be replaced at a fraction of the cost of the conductor wire. The shield 24 is preferably cut away at 25 where it is gripped by the clamp 11 to permit the plates 19 of the lugs or members 15 passing 75 over said shield.

As a modification of the connection between the lugs or members 14, 15, above the wire, the plates 19 with their hooked ends 18 engaging the slots 17 in complementary 80 members may be omitted, and perforations made in the upper ends of said members for a bolt 26, see Fig. 5, which is passed through said perforations and secured by a nut 27. If desired a filling block 28 may be inserted 85 between the upper ends of the members 14, 15, or between the upstanding portions of the shield 24, through which block the bolt 26 extends.

What I claim is:—

1. An insulator clamp comprising a pair of like separable sections adapted to grip a conductor and embrace an insulator, separable integral connecting means connecting said sections on one side of said conductor, and removable connecting means on the other side. 90

2. An insulator clamp comprising a pair of like separable sections adapted to grip a conductor and embrace an insulator, integral lugs on the ends of said sections provided with inter-engaging connecting means connecting said sections, and removable connecting means between said sections for securing them together. 100

3. An insulator clamp comprising a pair of like separable sections adapted to grip a conductor and embrace an insulator, an extension on one end of each section provided with a hook-ended projection, an extension 110 on the other end of each section having means for engaging said hook-ended projection, and removable connecting means between the complementary extensions of each section. 115

4. An insulator clamp comprising a pair of like separable sections, each having an integral conductor gripping extension on one end connected on one side of the conductor to a complementary extension on the 120 other section, and removable securing means between the sections on the other side of the conductor for fastening said gripping extensions firmly to the conductor and the clamp sections together upon an insulator. 125

5. An insulator clamp comprising a pair of like separable sections, each having an integral conductor gripping extension with a slot therein on one end and formed on the other end with a hook to connect to the slot 130

in a complementary member on the other section, and removable securing means between said sections for fastening said gripping extension firmly to the conductor and attaching the clamp sections together upon an insulator.

6. An insulator clamp comprising a pair of like separable sections, from the ends of which project conductor gripping extensions, one of said extensions on each section having engaging means for engaging the complementary member on the other section to lock said engaging means together, and removable connecting means between the sections.

7. An insulator clamp comprising a pair of like separable sections, from the ends of which project conductor gripping extensions, one of said extensions on each section having a laterally projecting plate terminating in a hook for engaging a slot in the complementary extension on the other section, and removable connecting means between the sections.

25 8. A clamp for connecting an insulator to a conductor consisting of a clamp-section

having means for engaging the conductor and the insulator, said clamp-section having dissimilar ends, and a second clamp-section like the first named clamp-section, said 30 clamp sections having integral means at their ends for interlocking said clamp sections when held in a reversed position with respect to each other, and means for drawing said clamp-sections together. 35

9. A clamp for attaching an insulator to a conductor, consisting of a pair of clamp-sections, having means for engaging the insulator and the conductor, said clamp-sections having extensions of the same mechanical shape having integral means for interlocking said clamp sections and preventing a lateral movement of said sections at the interlocked point, and means for drawing said clamp sections together. 40 45

In testimony whereof I have hereunto set my hand in presence of two subscribing witnesses.
